UNITED STATES PATENT OFFICE.

GEORGE NEWTON McDONALD AND NATHAN WARD FITZ-GERALD, OF
WASHINGTON, DISTRICT OF COLUMBIA.

DESIGN FOR A MILK-JAR.

SPECIFICATION forming part of Design No. 35,473, dated December 24, 1901.

Application filed October 28, 1901. Serial No. 80,351. Term of patent 7 years.

To all whom it may concern:

Be it known that we, GEORGE NEWTON McDONALD and NATHAN WARD FITZ-GERALD, citizens of the United States, residing at Washington, District of Columbia, have invented and produced a new and original Design for Milk-Jars; and we do hereby declare the following to be a full, clear, and exact description of the same, reference being had to the accompanying drawings, forming a part thereof.

Figure 1 is a plan view of a milk-jar, showing our new design. Fig. 2 is a side view thereof.

The leading and material feature of our new design is a milk-jar having the upper portion provided with flanges extended en-

tirely across the mouth of the jar, the upper edge of the mouth being slightly curved or convex, and a groove extends under the flanges. The outer sides of the flanges are parallel, as shown in the accompanying drawings.

What we claim is—

The design for a milk-jar as shown and described.

In testimony whereof we affix our signatures in presence of two witnesses.

GEORGE NEWTON McDONALD,
NATHAN WARD FITZ-GERALD.

Witnesses:

KIRKWOOD FLORA,
HENRY L. STINE.
